(57) **CLAIM**

The ornamental design for a wristwatch, as shown and described.

DESCRIPTION

FIG. 1 is a top view of the watch portion of my new and ornamental design for a wristwatch.

FIG. 2 is a bottom view thereof;

FIG. 3 is a right side view thereof;

FIG. 4 is a left side view thereof;

FIG. 5 is a front view thereof;

FIG. 6 is a rear view thereof

FIG. 7 is a right perspective view thereof;

FIG. 8 is a left perspective view thereof;

FIG. 9 is a top view of the bracelet portion of my new and ornamental design for a wristwatch;

FIG. 10 is a bottom view thereof;

FIG. 11 is a right side view thereof, the left side being a mirror image thereof; and,

FIG. 12 is a right perspective view thereof.

The watch and band portions of the wristwatch are shown separately for ease of illustration.
